WALL BRACKET LAMP

Edward Kanter, Cleveland Heights, Ohio

Application March 21, 1934, Serial No. 716,608

4 Claims. (Cl. 240—73)

This invention relates to a wall bracket lamp and has for its general object to provide a lamp of this character which shall be readily portable, attractive, easily adjustable, durable and inexpensive and which shall be effective to supply indirect lighting and while being constructed entirely of opaque material will give the impression of containing frosted glass.

A more limited object is the provision of unique means for concealing the wiring and at the same time supporting the weight of the electric cable from which current is supplied and the force of any shocks which might be imparted therethrough. A further object is the provision of unique means for assembling the shade elements.

Still further objects will become apparent from the following description when read in connection with the accompanying drawings in which Fig. 1 is a side elevation of my improved bracket lamp; Fig. 2 is a front elevation thereof; Fig. 3 is a partial sectional view; Fig. 4 is a section on the line 4—4 of Fig. 3; and Fig. 5 is a fragmentary elevation showing a portion of the wall engaging plate.

Referring now to the accompanying drawings the numeral 10 indicates a channel shaped wall engaging plate which is provided with side flange elements 11 extending along the middle portion thereof. At the upper and lower ends of the plate 10, the width is greatly decreased so that the said plate terminates in relatively narrow channel shaped portions 12. The channels of the portions 12 communicate with the main channel defined between the flanges 11. Adjacent the lower end of the flanges 11 is an opening 13 through the plate 10. On each side of the opening 13 are ears 14 between which is pivoted the lower end of an arm 15 by means of a pin 16. Immediately below the opening 13 is a cam portion 17 against which bears an adjusting screw 18 threaded through a lower portion 19 of the arm 15. Adjacent the upper ends of the flanges 11 is a suspension opening 20 which is adapted to receive a headed member 21 such as a push pin inserted into a wall 22, along which the flanges 11 and the flanges of the terminal portions 12 extend and against which they engage.

The arm 15, in the instant construction, is circular and of channel cross section as clearly indicated in Fig. 4. This arm terminates at its upper end in an outwardly bent portion 23 to which is pivoted an element 24 carrying a socket or receptacle 25 which may have a conventional push button switch 26. The socket 25 is provided with a shoulder 27 and a reduced externally threaded

portion 28. The electric cable 29 which supplies current to the socket 25 passes downwardly through the channel in the arm 15, through the opening 13 and downwardly through the channel in the lower terminal portion 12 of the plate 10. Short wire members 30 may be attached to the edges of the channels and bent over to hold the cable 29 in position.

Mounted on the socket 25 is a shade assembly adapted to give indirect lighting and which includes shade elements 31, 32 and 33, it being understood that no particular number of shade elements is essential and that the number employed is a matter of choice. These shade elements are supported in such manner as to extend in telescoping relation for a short distance and be considerably spaced apart to permit light to pass outwardly therebetween. This relation of shade elements I term "semi-nested". The lowermost shade element 31 has its lower and smaller end 10 engaging against the shoulder 27 and flaring outwardly and surrounding the threaded portion 28 of the said socket. Received on the threaded portion 28 is an internally threaded annular member 34 which has an outwardly extending flange 15 engaging against the inner surface of the shade element 31 whereby to clamp the same firmly against the shoulder 27. The annular member 34 carries, by means of a plurality of straps 35, the upper shade elements, each of said straps 35 being fixedly secured to the member 34 and to those shade elements above the lowermost. A bulb 36 is received in the socket 25 and extends upwardly into the interior of each of the shade elements. As will be clear from the drawings, the suspension opening 20 and the lowermost channel 12 are centered with respect to the plate 10 and lie in the plane of symmetry of the shade assembly, the arm 15 and the plate 10.

I prefer to provide at least the shade elements 32 and 33 with light diffusing zones on their exterior surfaces preferably by coating such zones with a flat finish, slightly gray paint or lacquer. When the color is about the shade of gray known as "oyster shell", the effect produced when illuminated is strikingly similar to frosted glass or similar translucent material.

While I have shown and described the preferred embodiment of my invention I wish it understood that the same may be embodied in varying forms and that I am limited only in accordance with the appended claims and the prior art.

Having thus described my invention, what I claim is:

1. In combination with a socket having an externally threaded portion and a shoulder, of a shade element engaging against said shoulder and flaring away from its shoulder engaging portion and surrounding and extending above said threaded socket portion, an internally threaded annular member received on the threaded portion of the socket and engaging the inner surface of said shade element, and a second similarly flaring shade element carried, at a point spaced from said socket, by said annular member and being semi-nested with said first shade element.
2. In combination with a socket having an externally threaded portion and a shoulder, a shade element engaging against said shoulder and flaring away from its shoulder engaging portion and surrounding and extending above said threaded socket portion, an internally threaded annular member received on the threaded portion of the socket and engaging the inner surface of said shade element at a point spaced from said socket, and a plurality of connected, similarly flaring, semi-nested shade elements carried by said annular member, the lowermost thereof being semi-nested with the first said shade element.
3. A wall bracket lamp comprising a channel-shaped wall-engaging plate, a pair of ears carried by said plate, an arm pivotally supported between said pair of ears and having a projection thereon,
- 5 a lamp socket and shade carried by the outer portion of said arm, said plate having an opening therein adjacent said pair of ears, said plate having a narrow channel portion extending downwardly from a point adjacent said opening, an electric cable connected with said lamp socket and extending through said arm and through the opening in said plate and thence behind said narrow channel, and means carried by the projecting portion of said arm for adjusting the position of 10 said arm.
- 10 4. A wall bracket lamp comprising a channel-shaped wall-engaging plate, a pair of ears carried by said plate, an arm pivotally supported between said pair of ears and having a projection thereon, 15 a lamp socket and shade carried by the outer portion of said arm, said plate having an opening therein adjacent said pair of ears, said plate having a narrow channel portion extending downwardly from a point adjacent said opening, an electric cable connected with said lamp socket and extending through said arm and through the opening in said plate and thence behind said narrow channel, and means carried by the projecting portion of said arm for adjusting the position of 20 said arm, said arm being circular in shape and channel-shaped in cross section and being secured to said plate at a point opposite said lamp socket.
